UNITED STATES PATENT OFFICE.

VIGGO W. PALLESEN, OF COLLEGEVIEW, NEBRASKA, AND JUNIUS PAULSON, OF HUTCHINSON, MINNESOTA; SAID PAULSON ASSIGNOR TO SAID PALLESEN.

COMBINED FIRELESS COOKER AND RANGE.

1,073,924.

Specification of Letters Patent. Patented Sept. 23, 1913.

Application filed January 9, 1911, Serial No. 601,764. Renewed February 11, 1913. Serial No. 747,801.

To all whom it may concern:

Be it known that we, VIGGO W. PALLESEN and JUNIUS PAULSON, citizens of the United States, residing at Collegeview, in the 5 county of Lancaster and State of Nebraska, and Hutchinson, McLeod county, State of Minnesota, respectively, have invented certain new and useful Improvements in Combined Fireless Cookers and Ranges, of which 10 the following is a specification.

This invention relates to combined fireless cookers and stoves and is designed particularly to facilitate the operation of fireless cookers.

15 Whereas it is customary in this art to place the article to be cooked on the stove until the same has thoroughly absorbed the heat, and then place it in the fireless cooker for completion of the operation of cooking, 20 it is contemplated in this invention to provide a stove wherein the article may be heated and then without removal be isolated and brought to the desired state through the medium of the accumulated heat.

25 It also contemplates the construction of a combination range which will perform the functions heretofore described, but which will also permit the oven thereof to be used independently of the fireless cooker arrangement.

30 With the above and other objects in view, this invention consists in the construction, combination, and arrangement of parts, all as hereinafter more fully described, claimed, 35 and illustrated in the accompanying drawings, wherein—

Figure 1 is a vertical section of the stove constructed in accordance with the present invention; Fig. 2 is a horizontal section 40 thereof; Fig. 3 is a perspective view of the exterior of the stove; Fig. 4 is a similar view illustrating the tube adapted to conduct the heat from the burners to one of the fireless cooker compartments.

45 Referring more particularly to the drawings, 10 indicates a stove, the walls, top and bottom of which are constructed of spaced sheets of metal 10' between which is interposed the non-conductive material 11. A 50 door 12 similarly constructed, operates in the lower side in the front wall thereof and permits access to the oven or main compartment A located in the lower part of the stove. The upper part of the stove is divided into a series of auxiliary compartments 55 by the partition 13, each auxiliary

compartment being provided with a lid 14, said partition and lids being constructed similarly to the walls of the stove. A flange 15 is located about the lower side of each auxiliary compartment upon which the vessels B are adapted to rest. Each auxiliary compartment is provided with a door 16 which swings downwardly into the oven when it is desired to heat the vessel supported by the flange 15 and which rests horizontally when it is desired to close the auxiliary compartment forming the same into a fireless cooker. These doors are retained in their horizontal positions by the catches 17 which are pivotally mounted on the partition 13.

A plurality of burners 18 are located in the bottom of the oven A and provide a means whereby the oven may be heated directly from said burners. In order to provide a means whereby heat may be conducted from each burner to the corresponding auxiliary compartment when it is desired to heat the vessels which may be placed in the 80 cooker compartments, a collapsible tube 19 is located over each burner, the lower section of which is provided with a U-shaped bracket 20 which is pivotally connected to the burner. The terminals of the collapsible 85 tubes 19 are flared to provide the heat collecting and distributing elements. In order to retain the tubes in their vertical positions, a spring catch 21 is carried by each burner 18 opposite to the bracket 20, and engages 90 the periphery of the heat collecting element of the corresponding tube.

From the foregoing it will readily be understood that when it is desired to use the auxiliary compartments as fireless cookers, 95 the doors 16 are locked in their horizontal positions. The tubes are then collapsed and released from engagement with the spring catches 21, and are allowed to rest upon the bottom of the oven A. The auxiliary compartments are then completely isolated from the main compartment of the stove and the cooking process of articles therein contained allowed to proceed independent of the oven or main compartment. The burners are then 100 free to heat the oven, and a series of shelves illustrated in dotted lines in Fig. 1 may be inserted to facilitate the use of said oven.

A shelf 22 is located upon the side of the stove underneath which is provided the 110 burner 23, the provision of which affords additional means for bringing the articles to

be cooked to a desired temperature before the same are placed in the auxiliary compartments.

It will furthermore be noted that the main compartment may also be used as a fireless cooker, if so desired. To accomplish this function when the oven has been heated to a sufficient degree which may be indicated by a thermometer 24 located in the door, the 10 gas may be turned off and the cooking process continued as in the operation of the auxiliary compartments hereinbefore fully described, without the necessity of opening the door and allowing the accumulated heat to 15 escape.

The cooker hereinbefore described is so designed that it may take the place of a fireless cooker, range, steam-table, coffee-urn, etc. One of the principal features is that of 20 placing a heating device in a way so that the various compartments may be heated independently. This will enable cooking without first placing the food on a stove until heat enough has been absorbed to complete 25 the cooking.

For heating function may be used either gas, gasoline, or electricity. In the first event devices as described above will be used. In the latter an electric heating device is 30 placed in the bottom of each compartment.

Having thus fully described our invention, what is claimed as new is:—

1. A stove having walls of non-conductive material and comprising a main compartment, a source of heat for said compartment, auxiliary compartments having openings in the bottoms thereof located above said main compartment, a door pivotally mounted at the bottom of each auxiliary compartment 40 and adapted to close the bottom of same, and pivotally mounted collapsible tubes over said source of heat for conducting heat directly to each of said latter compartments.

2. A stove having walls of non-conductive material and comprising a main compartment, a source of heat adjacent to the base of said main compartment, auxiliary compartments having openings in the bottoms thereof located above the main compartment, means for isolating the auxiliary compartments from the main compartment, and means above said source of heat for directly conducting heat to the auxiliary compartments and movable bodily in the main compartment to permit the heat to pass directly into the latter when isolated from the afore-said auxiliary compartments.

3. A stove having walls of non-conductive material and comprising a main compartment, burners in the bottom of said main compartment, auxiliary compartments having openings in the bottoms thereof located above said main compartment, a door pivot-

ally mounted at the bottom of each auxiliary compartment and adapted to close the 65 bottom of same, collapsible tubes mounted over said burners for directly conducting heat to each of said auxiliary compartments, means for holding said doors in a horizontal position whereby each auxiliary compartment 70 may be isolated from the main compartment, means for holding said tubes in a vertical position, and a door for said main compartment.

4. A stove having walls of non-conductive 75 material and comprising a main compartment, burners in the bottom of said main compartment, auxiliary compartments having openings in the bottoms thereof located above said main compartment, a door pivotally mounted at the bottom of each auxiliary compartment and adapted to close the bottom of same, collapsible tubes mounted over 80 said burners for directly conducting heat to each of said auxiliary compartments, means for holding said doors in a horizontal position 85 whereby each auxiliary compartment may be isolated from the main compartment, means for holding said tubes in a vertical position, a door for said main compartment, 90 and means for supporting shelves in said main compartment.

5. A stove having walls of non-conductive material and comprising a main compartment, burners located in the bottom of said 95 compartment, auxiliary compartments having openings in the bottoms thereof located above the main compartment and having flanges about their lower sides for supporting vessels therein, a door pivotally mounted at the bottom of each auxiliary compartment and adapted to close the bottom of same, collapsible tubes flared at their opposite ends pivotally mounted over said burners and adapted to conduct heat directly to 105 said auxiliary compartments, a spring catch to hold said tube in a vertical position when the door of the corresponding auxiliary compartment is open, a catch for holding the door in a horizontal position when it is desired to isolate the auxiliary compartment, flanges disposed on the opposite sides of the main compartment for supporting shelves, and a door for said latter compartment.

In testimony whereof I affix my signature 115 in presence of two witnesses.

VIGGO W. PALLESEN.
